AUTOMATIC TELEPHONE SYSTEM

John H. Voss, Downers Grove, Ill., assignor to
 Associated Electric Laboratories, Inc., Chicago,
 Ill., a corporation of Delaware

Application October 1, 1936, Serial No. 103,490

21 Claims. (Cl. 179—18)

The present invention relates in general to automatic telephone systems and more in particular to small automatic telephone systems which are adapted for use in rural communities. 5 An automatic system of this type is generally known as a community automatic exchange or C. A. X. In systems of this kind it is the usual practice to provide for multi-station party lines having either bridged or grounded ringing circuits, or combinations of each, and the subscribers are signalled by means of code ringing equipment. It is also customary to provide trunking facilities for extending connections to distant switching centers which may be either manual 10 or automatic exchanges. The object of the invention may be stated to be the provision of a new and improved telephone system of this character.

One of the features of the invention relates 20 to an improved link circuit comprising a non-numerical line-finder switch for finding a calling line, and a numerical connector switch for extending a connection to a called line, or to an idle trunk line to a distant exchange. The link circuit is arranged to operate directly into a manual or automatic switching center without the use of a repeater.

A further feature is in the arrangement used 30 to provide a holding circuit for the link when a call is extended to a distant manual exchange or a distant automatic exchange. The release of the link circuit is controlled by the operator, when a call is extended to a manual exchange, and by the called subscriber, when a call is extended to 35 a distant automatic exchange.

A still further feature of the invention relates 40 to a new arrangement for assigning a different link circuit on successive calls by subscribers.

The foregoing objects and features of this invention together with others not specifically mentioned at this time will be described hereinafter 45 with reference to the accompanying drawings, which show by means of the usual circuit diagrams sufficient of the apparatus involved to enable the invention to be readily understood.

Referring to the drawings, Figs. 1, 2, and 3, when placed in alignment, show the equipment 50 for extending a connection from a calling subscriber to a called subscriber. Fig. 4, on the same sheet with Fig. 3, shows the line equipment at a distant automatic exchange, together with additional relays required to hold the C. A. X. equipment until the switches at the distant automatic exchange have been released by the called subscriber.

Considering the drawings more in detail, Fig. 1 shows a full metallic common battery party line and the associated line circuit at the C. A. X. 55 The subscriber's station A represents one of a plurality of subscribers' stations that can be con-

nected to a line. A line may have as many as ten stations, divided ringing being used. This means that the subscribers are signalled by means of code ringing, half the ringers being connected from one side of the line to ground, and the other half being connected from the other side of the line to ground. It will be understood that various other types of lines may be connected to the C. A. X., such as individual lines and party lines with bridged ringers. Lines of this kind 10 will be described later on in connection with the operation of the systems.

Connections between the various subscribers' lines in the system and connections from a subscriber's line to an outgoing trunk line are established by means of finder connector links. One of these links is shown in Figs. 1, 2, and 3 of the drawings. It comprises a finder switch, Fig. 1, which is indicated by the designation Finder; a code-selecting switch and a connector switch, 20 Fig. 3, which are indicated by the designations Code switch and Connector, respectively. These switches are preferably rotary 25-point switches and are similar to the switch disclosed in Patent 1,693,027, granted to John Erickson, November 25 27, 1928. These switches are of the step-by-step type in which the wipers move in a forward direction only, and in which the wipers are advanced when the stepping magnet retracts its armature rather than when it attracts its armature. The link also comprises a number of relays which are shown in Figs. 1, 2, and 3, and a repeating coil shown in Fig. 2.

The allotter circuit shown in Fig. 1, comprising a start relay and two link selecting relays, 35 controls the starting and selection of the finder-connector link. The allotter is common to two link circuits in this particular system and is arranged to start both idle links to find a calling subscribers' line or to start the idle link if one 40 of the links is busy. The allotter is also arranged to assign a different link circuit to find a calling subscriber's line circuit on successive calls.

As mentioned hereinbefore, Fig. 4 shows a trunk line to a distant exchange terminating in 45 a regular subscriber's line circuit which comprises the usual line, cut-off, and lock-out relays, together with a start relay and a battery-reversing relay. When a call is extended over the trunk line from the C. A. X. to the distant automatic 50 exchange, the battery reversing relay is held operated, thereby holding the link circuit in the C. A. X. in an operated position. The release of the connection is under control of the called subscriber at the distant automatic exchange. 55

The operation of the system will now be described, it being assumed for this purpose that the subscriber at station A desires to call a subscriber at station B. When the subscriber at station A removes his receiver a circuit is com- 60

pleted for line relay 1. This circuit is from battery through the upper winding of line relay 1, through contacts 21 of cut-off relay 2, line conductor 28, station equipment A, line conductor 29, lower winding of line relay 1, armature 20 of cut-off relay 2 to ground. Line relay 1 operates, and at armature 23 it connects ground to the private normal conductor 31, thereby rendering the calling line busy in the banks of the connector switches. At contact 22, line relay 1 connects the cut-off relay 2 to conductor 32 in the finder bank. This operation marks the line as calling to the banks of the finder switches, the other terminal of cut-off relay 2 being connected 10 to battery. In addition, line relay 1 places ground on the allotter start conductor 30 at armature 24.

The ground potential applied to conductor 30 causes the allotter start relay 4 to energize. At 20 armature 33, allotter start relay 4 places battery on link #1 start conductor 40, and at armature 35 places battery on link #2 start conductor 41. Start relay 4 also connects battery by way of armature 34, and the normally closed contacts 25 of armature 37 on relay 5, to the upper winding of relays 5 and 6, to ground. In addition, battery is also connected by way of armature 39 through the lower portion of relay 6 to ground. Link #2 selecting relay 6 does not operate because its 30 windings are in opposition to each other. However, #1 link selecting relay 5 operates by way of the above described circuit and locks itself up to battery by way of armature 37. At armature 36, link-selecting relay 5 opens part of the stopping 35 circuit of the finder in link #2.

The four conductors A1, B1, A and B, extending to link #2, are designated A, B, A1, and B1, respectively, extending to link #1, as is shown to the right of the allotter. The conductors designated A, B, A1, and B1 of link #2 are reversed as they extend to link #1 so that conductors A and B of link #2 connect to conductors A1 and B1, respectively, of link #1; also, conductors A1 and B1 of link #2 connect to conductors A and B, respectively, of link #1. The reason for this reversal in conductors between links #1 and #2 will be understood from the detail description of the operation.

The placing of battery on the link-start conductor 40, due to the operation of start relay 4 in the allotter, completes a circuit for start relay 10 in link #1, from battery on conductor 40, winding of start relay 10, armature 42, armature 43, conductor 44, bank contact 303 of the connector 50 portion of the link 1, wiper 304, to ground. Relay 10 operates, and at armature 46 opens the stopping circuit to the finder in link 2. At armature 47, start relay 10 completes a circuit for the rotary stepping magnet 7. This circuit is completed 55 from battery at the rotary stepping magnet 7, armature 58, armature 47, armature 42, over two paths to the grounded conductor 44, one of which is through armature 48 on start relay 10 and the other of which is on armature 43 of supervisory timer relay 15. In addition, at armature 45 start 60 relay 10 also prepares a stopping circuit for the finder switch. This circuit includes the lower winding of switching relay 9, conductor B, armature 38 of the relay 6 of the allotter, conductor A, lower winding of stepping relay 8, and wiper 60 65 of the finder switch. At armature 44, relay 10 prepares a circuit which will be described later, and at armature 43 completes a circuit for line relay 19, which includes resistance 50 and the upper winding of line relay 19. Line relay 19 oper-

ates, and at armature 51 completes a circuit for lock-pulse relay 12 which may be traced from battery through the winding of lock-pulse relay 12, armature 51, armature 57 on relay 17, to the normally closed contacts controlled by armature 61, to ground. In response to the closing of this circuit the lock-pulse relay 12 operates and at armature 52 completes a circuit for the operation of release relay 16. At armature 53, lock-pulse relay 12 completes a locking circuit for itself by 10 way of resistance 62 and armature 51. In response to the operation of release relay 16, auxiliary release relay 17 is operated over the following circuit: ground at the normally closed contacts controlled by armature 61, contacts at armature 54, conductor 72, armature 212, armature 213, conductor 71, winding of auxiliary release relay 17, to battery. Another path for the circuit for relay 17 may also be traced by way of contact 63 of reverting call relay 11. Auxiliary 20 release relay 17 operates, and at armature 56 grounds the interrupter start lead by way of armature 101, conductor 69, armature 215, and at armature 100 places a ground potential on conductor 91. At armature 55 it connects the supervisory timer relay 15 to the time-pulse conductor TP. 25

The timing equipment momentarily grounds conductor TP at the beginning of each timing cycle and completes a circuit for supervisory timer 30 relay 15 over the following path: conductor TP, normally closed contacts controlled by armature 64, armature 55, armature 65, conductor 66, armature 214, conductor 68, winding of supervisory timer relay 15, to battery. Relay 15 operates and 35 completes a locking circuit for itself at armature 64 and its front contact; replaces the ground at the normally closed contacts controlled by armature 61 to the CO conductor from the timer, which is grounded during the timing cycle, at armature 61 and its front contact; and at armature 43 opens the circuit of start relay 10, to prevent the link from being seized during the ringing period on reverting calls. The ground potential is maintained on the cut-off conductor CO 40 for at least two minutes. After this period of time has elapsed and the calling subscriber has not dialled, or if the called subscriber has not 45 answered, or if there is a permanent on the line which would cause the operation of the equipment, the ground is removed from conductor CO. When this occurs all relays locked to the CO conductor will release thereby causing the entire link to restore to normal. 50

The operation that has taken place has been 55 due to the grounding of the start conductor 40, and it should be understood that the same operations have taken place in link #2. By referring back to the operation of the rotary magnet 7, a description will be given of the stepping action 60 of the finder switch portion of the link #1 in its search for the calling line.

In response to the operation of the rotary magnet 7, contacts 104 are closed and stepping relay 8 is energized. The energization of the rotary 65 magnet 7 also prepares for the advancement of wipers 60, 102, and 103, to the next bank contacts of the finder switch. This action takes place because of the operation of stepping relay 8, which at armature 58 opens the operating circuit of 70 rotary magnet 7, thereby causing the advancement of the wipers to the next set of bank contacts. At armature 104, rotary magnet 7 also opens the circuit for the stepping relay 8, which falls back and at armature 58 again completes 75

the energizing circuit for rotary magnet 7. The interaction between stepping relay 8 and rotary magnet 7 continues, thereby advancing the wipers 60, 102, and 103, over the bank contacts of the 5 finder switch.

When the wipers encounter the bank contacts of the calling line, a circuit is completed from battery at the winding of cut-off relay 2, armature 26, armature 22 of the operated line relay 10 1, conductor 32 and its associated bank contact, wiper 60, lower winding of stepping relay 8, conductor A, armature 38, conductor B, lower winding of switching relay 9, armature 45, to ground. Cut-off relay 2 in the line circuit, stepping relay 8, and switching relay 9, all operate in series. The operation of stepping relay 8 prevents further advancement of the wipers because the circuit for the rotary magnet 7 is held open at armature 58. Switching relay 9 locks 20 up from battery by way of its upper winding, armature 105, armature 106, armature and lower contact 54, armature 61, to ground on the cut-off conductor CO. At armature 107, switching relay 9 places a ground potential on conductor 25 30 of the allotter to maintain start relay 4 in an energized position. This circuit is completed to maintain start relay 4 of the allotter in an operated position until start relay 10 in the link falls back, due to the opening of armature 42 30 by the operation of switching relay 9. It should be noted that the ground potential which is used in the locking circuit for switching relay 9 also extends by way of armature 108 and wiper 60 of the finder switch to the cut-off relay 2 in the 35 line circuit. When switching relay 9 operates and closes armature and contact 108 to insure the operation of cut-off relay 2, stepping relay 8 releases slowly because of the ground potential connected to both sides of the lower winding over the following circuit: ground on cut-off conductor CO, armature 61, armature 54 and 40 its front contact, armature 108, lower winding of stepping relay 8, conductor A, armature 38, conductor B, lower winding of relay 9, armature 45 to ground. This slow action in releasing of 45 stepping relay 8 prevents contacts 58 from closing before start relay 10 has had time to fall back. Switching relay 9 also connects the subscriber's line conductors 28 and 29 through 50 to the line relay 19 in the link circuit, by way of its armatures 109 and 110.

Referring back to the operation of cut-off relay 2 of the line circuit, it will be noted that at armatures 20 and 21 line relay 21 is disconnected from the subscriber's line conductors 28 and 29. 55 However, battery and ground potential is now supplied to the calling subscriber by way of the winding of line relay 19 of the link #1. At armature 21, relay 2 completes a locking circuit for itself by way of the grounded conductor 32, and when line relay 1 falls back, this ground potential is extended by way of armature 23 of line relay 1 to the private normal conductor 31, to maintain a busy condition on the connector bank contacts. In addition, cut-off relay 2 at armature 20, completes an energizing circuit for 60 lockout relay 3. Lockout relay 3 on energizing, opens the initial operating circuit for cut-off relay 2 at armature 26, and at armature 25 opens a point in the start circuit over conductor 30 to the allotter.

Referring back to the start relay 10 in the link whose circuit was opened by the operation of the switching relay 9. Relay 10 falls back and at armature 44 removes ground potential from the 70

start conductor 30, which allows relay 4 in the allotter to deenergize. In addition, start relay 10, upon falling back, opens the circuit at armature 45 through the lower winding of switching relay 9 which is of no avail because relay 9 is locked 5 in an energized position by way of its upper winding. It prepares a stopping circuit for the finder in link #2 at armature 46; it prevents the operation of the rotary magnet 7 after stepping relay 8 is released at armature 47; and at 10 armature 49 prepares a circuit for the pick-up pulse from the code interrupter. The removal of ground from the upper winding of line relay 19, due to the deenergization of start relay 10, does not affect relay 19 at this time, because it 15 is held in an operated position over a circuit including both of the windings and the calling subscriber's station.

A description will now be given of what happens in the allotter circuit in response to the 20 restoration of start relay 4. At armatures 33 and 35 start relay 4 removes the battery potential from the start conductors 40 and 41 of links #1 and #2, respectively. Since link #1 has already been positioned and is connected to a calling line, the removal of battery from link start conductor 40 is of no consequence. However, the removal of battery from link start conductor 41 causes link #2 to cease 25 operating. The relays in link #2 are restored 30 to their normal position. However, it might be well to point out that the wipers controlled by the rotary magnet in link #2 remain engaged with the bank contacts of the finder to which they were positioned in response to the last de- 35 energization of the rotary magnet. In other words, the wipers of the finder switch do not have a normal or "home" position, and therefore, remain in engagement with the set of bank contacts. 40

Referring again to the release of start relay 4 of the allotter, it will be noted that at armature 34 battery is removed from the lower winding of link #2 selecting relay 6. Relay 6 now operates by way of a circuit including its upper 45 winding and armature 37 since there is no current flowing in the opposing lower winding. At armature 38, relay 6 opens the stopping circuit for link #1 by disconnecting the A and B conductors, and at armature 39 prepares a circuit 50 for the lower winding of link #1 selecting relay 5.

If another subscriber in the C. A. X makes a call, a line relay similar to line relay 1 of the line circuit shown in Fig. 1 operates and grounds 55 the allotter start conductor 30, causing the operation of start relay 4. Start relay 4 again connects battery to conductors 40 and 41 to start both finders, and at armature 34 closes a circuit to the lower winding of link #1 selecting relay 5. 60 This causes relay 5 to release. With relay 5 in its normal position, and relay 6 operated, the start relay in link #2, which is the same as the start relay 10 in link #1, will open the stopping circuit for link #1. The stopping circuit for the 65 finder in link #2 is now closed at armature 36 of the allotter due to the restoration of relay 5, so that the calling line will be connected through link #2 when it is found. When the second calling line has been found by the finder in link #2, 70 start relay 4 of the allotter will restore to normal. When relay 4 releases, battery is removed from the upper winding of link #2 selecting relay 6, thereby causing relay 6 to restore to its normal position. With link selecting relays 5 75

and 6 in their normal positions, the allotter is again in a position to assign link #1 to a calling line. With an allotter circuit of this kind, a different link will be assigned to the calling lines on successive calls.

When the link #1 was first seized and relay 10 operated, among other operations already explained, release relay 16 and auxiliary release relay 17 were operated. At armatures 100 and 111 a ground potential was applied to conductor 91, by the operation of relays 16 and 17, and at armature 56 ground was extended by way of armature 101, conductor 69, armature 215, to the interrupter start conductor to start the code interrupter machine. The ground potential applied to conductor 86 at armature 112 has no effect at this time. However, the ground potential applied to conductor 91 by the closing of armatures 100 and 111 completes a circuit over one path including the wiper 309 of the code switch and its associated bank contact and the lower winding of unit series relay 210 by way of conductor 216. The circuit over the other path includes the wiper 305 of the connector switch and its normal or home bank contact, conductor 217, and the upper winding of the tens series relay 208 to battery. The operation of the tens series relay 208 connects the dial tone to the calling subscriber's line over the following path: dial tone conductor DT, armature 218, condenser, armature 227, armature 237, upper right-hand winding of the repeating coil, armature 238, normally closed contacts controlled by armature 241, lower winding of back-bridge relay 205 to ground. The dial tone is induced in the upper left-hand winding of the repeating coil over the upper line conductor to the calling subscriber. At armature 221, the tens series relay 208 prepares a locking circuit for itself and at armature 220 prepares a circuit for operating the rotary magnet 301 of the connector portion of link #1. The opening of contacts 219 by the relay 208 opens a point in the restoring circuit for the rotary magnet 301 which will be explained more in detail later.

In response to the operation of unit series relay 210, auxiliary relay 211 is operated from ground at armature 224; a holding or locking circuit is prepared at armature 222 for the upper winding of relay 210; and at armature 223 a circuit is prepared for the ring cut-off relay 206 which is effective only when the wipers of the connector switch are controlled by a calling subscriber who desires to make a call over the trunk. Upon operating, auxiliary relay 211 disconnects the busy tone conductor BC from the link circuit at armature 258; prepares an operating circuit for the rotary magnet 302 of the code switch at armature 259; connects the busy relay 209 through to the wiper 306 of the connector, thereby preparing the line busy test at armature 260; at armature 261 opens a point in the circuit for restoring the wipers of the code switch to their normal or "home" position; and at armature 262 opens a point in the circuit for the #1 pulse timer relay 14.

The link circuit now is in a position to receive the impulses transmitted in response to the operation of the calling device or dial by the calling subscriber. It will be assumed that the subscriber at station A desires to talk to the subscriber at station B whose number is 45. It may be well to mention at this time, that the subscriber's line number consists of two digits. The first digit controls the connector switch in the

link circuit to select the line, and the second digit controls the code switch in the link to select the ringing code to be transmitted over the line.

When the subscriber at station A operates his calling device for the first digit 4, the circuit for line relay 19 in the link is interrupted momentarily four times by the impulse springs of the calling device in the usual and well known manner. The operating circuit for line relay 19 is from ground, lower winding of relay 19, normally closed contacts controlled by armature 113, conductor 77, lower left-hand winding of the repeating coil, conductor 132, armature 110, wiper 102 of the finder switch, conductor 29, substation A, conductor 28, wiper 103 of the finder switch, armature 109, conductor 76, upper left-hand winding of the repeating coil, conductor 78, normally closed contacts controlled by armature 114, upper winding of line relay 19, to battery. The line relay 19 is maintained in an operated position over this loop circuit, and each time this circuit is momentarily interrupted by the impulse springs of the calling device at station A, line relay 19 falls back and momentarily completes a circuit at the back contact of armature 51 and by this same action momentarily opens the circuit to the lock-pulse relay 12. Each time relay 12 falls back, a circuit is completed through the back contact of armature 116 for operating the rotary magnet 301 of the connector switch and a holding circuit by way of the lower winding of the tens series relay 208. This circuit is from ground on cut-off conductor CO, armature 61 of the timer relay 15, front contacts of armature 57, back contacts of armature 116, conductor 79, over one path including the front contacts of armature 221 and the lower winding of tens series relay 208 to battery; and over the other path including armature 220, conductor 241, winding of rotary magnet 301, to battery. Series relay 208 is maintained in operated position over this circuit. The rotary magnet 301 upon operating, completes a circuit from ground, armature 313, conductor 81, armature 51 and its resting contact, resistance 115, armature 117, resistance 50, upper winding of line relay 19 to battery. Line relay 19 is only partially energized over this circuit due to the resistances 50 and 115 and does not energize sufficiently to operate its armature 151. The reason for this partial energizing circuit of relay 19 is provided so that the line relays will operate faster when its circuit, including the upper and lower windings, is closed again by the impulse springs of the calling subscriber's dial. When the impulse springs of the dial are closed again, line relay 19 operates and at armature 51 again completes the circuit from ground at the cut-off conductor CO to the lock-pulse relay 12. Lock-pulse relay 12 upon energizing completes a locking circuit for itself at armature 53 by way of the resistance 62 and armature 51 of the line relay, and at armature 116 and its back contact opens the circuit for the tens series relay 208 and the rotary magnet 301 of the connector. When the rotary magnet 301 falls back, wipers 304 to 308, inclusive, are advanced one step. In response to the dialing of digit 4, line relay 19 and lock-pulse relay 12 fall back four times thereby controlling the rotary magnet 301 so that its wipers 304 to 308, inclusive, are advanced into engagement with the fourth set of bank contacts of the connector switch.

It should be noted that each time a circuit is completed for the rotary magnet the circuit is also completed to the lower winding of the tens series

relay 208. Relay 208 does not fall back each time the circuit is opened for the rotary magnet 301, due to the fact that the copper sleeve around its core makes it slow to release. Auxiliary relay 16, which is maintained in an energized position from ground at armature 52 of the lock-pulse relay, is also a slow-to-release relay due to the sleeve around its core and does not fall back during the momentary interruption of the lock-pulse relay 12. 10 When wipers 304-308, inclusive, of the connector switch are advanced into engagement with the calling line in response to the first digit dialled, a battery potential would be encountered on conductor 314 if the line is idle, and a ground 15 potential would be applied thereon if the called line is busy. The ground or battery potential, as the case may be, is applied from the line circuit of the called subscriber's line. If the line is busy the ground potential on conductor 314 completes 20 a circuit for the busy test relay 209 by way of wiper 306 of the connector switch, conductor 248, armature 260 and its front contact, winding of busy test relay 209 to battery. The busy test relay operates at this time but the busy tone applied 25 to conductor BT by the tone relays is not connected to the calling subscriber's line until the release of auxiliary relay 211 after the code switch has been set by the dialling of the second digit. If the called line is idle, battery potential 30 on 314 does not have any effect on the busy test relay, therefore it does not operate. However, the busy test relay is connected to the called line by way of armature 260 of the auxiliary relay 211 during the dialling period required to set the code 35 switch.

After the first series of impulses has been completed, the slow-to-release tens series relay 208 falls back, and at armature 221 and its resting contact prepares the circuit for the rotary magnet 302 of the code switch and the slow-to-release 40 unit series relay 210. In addition, dial tone is disconnected from the calling subscriber's line at armature 218; the circuit for restoring the wipers of the connector switch to normal is prepared at 45 armature 219; and at armature 220 the impulsive circuit for the rotary magnet 301 is opened.

The subscriber at station A now dials the second digit of the wanted subscriber's number, which is in this case, the digit 5. Each time the line relay 19 falls back in response to the interruption in its circuit by the impulse springs of the dial, lock-pulse relay 12 falls back as has been described before. At armature 116 the circuit for rotary magnet 302 of the code switch 50 and the circuit for the unit series relay 210 is completed as follows: from the grounded cut-off conductor CO, armature 61 and its front contact, armature 57 and its front contact, armature 116 and its back contact, conductor 79, armature 221 and its resting contact, over one path including armature 222 and the upper winding of series relay 210 to battery; and over another path including armature 259, conductor 252, winding of rotary magnet 302 of the code 55 switch to battery. At armature 315, rotary magnet 302 grounds conductor 81 in the same manner as described in connection with the operation of rotary magnet 301 of the connector switch. Ground on conductor 81 operates lock-pulse relay 12 as soon as the line relay 19 operates at the 60 termination of the first pulse. Lock-pulse relay 12 opens the circuit for the rotary magnet 302 of the code switch, causing it to release, thereby advancing its wipers 309-312, inclusive, into engagement with the first set of bank contacts. 65

The operating circuit for units series relay 210 over its lower winding, is opened as soon as wiper 309 is advanced from the normal or "home" position of the code bank. However, relay 210 is slow to release and is maintained in an energized position due to the momentary circuit completed over its upper winding each time lock-pulse relay 12 falls back. The circuit for the line relay 19 and lock-pulse relay 12 is momentarily opened in response to the dialling of digit 10 5 by the calling subscriber. Consequently, rotary magnet 302 of the code switch advances wipers 309-312, inclusive, into engagement with the fifth set of bank contacts of the code switch. 15

It will be assumed that the subscriber at station B whose number is 45 is busy. Therefore, the ground potential on conductor 314 has caused the operation of the busy test relay 209 as has been described. On completion of the dialling of the last digit, unit series relay 210 releases, and 20 at armature 224 opens the circuit for auxiliary relay 211. When auxiliary relay 211 falls back the circuit for the busy test relay 209 is transferred from the front contact of armature 260, to the resting contact controlled by the front 25 contact of armature 260. When this transfer in the circuit for the busy test relay is made relay 209 completes a locking circuit by way of its front contact at armature 258, conductor 82, armature 57 and its front contact, armature 61 30 and its front contact, to the grounded cut-off conductor CO. The busy tone is now connected to the calling subscriber's line from busy tone conductor BF, armature 258 of the auxiliary relay 211, armature 259, over the same path described 35 for transmitting dial tone to the calling subscriber. The calling subscriber upon hearing the busy signal will hang up his receiver thereby causing the release of the entire connection. 40

It will be assumed now that the called line was found idle. Under this condition, conductor 314 of the called line will now be grounded when the wiper 306 engages the bank contact, and the busy test relay 209 will not operate. In view 45 of the fact that the busy relay 209 is not operated and auxiliary relay 211 has fallen back, a circuit is completed from the grounded cut-off conductor CO, armature 61 and its front contact, armature 57 and its front contact, conductor 50 28, armature 258 and its resting contact, armature 260 and its resting contact, conductor 248, wiper 306 of the connector switch and its associated fourth bank contact, conductor 314, to the cut-off relay in the called line circuit to 55 battery. The grounding of conductor 314 causes the operation of the cut-off relay of the called line, thereby removing its associated line relay from across the line, and in addition grounds the test bank contact accessible to the test wiper 60 of the connector portion of the link #2. At armature 259 auxiliary relay 211 disconnects the dialling circuit for the rotary magnet 302 and at armature 261 prepares a circuit for advancing the wipers of the code switch to their normal or 65 "home" position. The release of the unit series relay 210 completes an energizing circuit for the pick-up and switching relay 207 at armature 225. The circuit for the pick-up and switching relay 207 may be traced over the following 70 path: battery, upper winding of relay 207, armature 225, armature 259, conductor 93, armature 120, armature 49, pick-up conductor PU, to the code interrupter. 75

At the beginning of each code cycle of the code 75

interrupter machine, or code interrupter relays, as the case may be, the code interrupter momentarily grounds the pick-up lead PU thereby operating the pick-up and switching relays 207. 5 Relay 207 operates and locks itself in an energized position to the grounded conductor 91 by way of its lower winding and armature 231. At armatures 226, 228, 229, and 230, pick-up and switching relays 207 prepare the ringing circuit 10 to the called subscriber's line. The code interrupter now transmits ringing code over conductors 1 to 5, inclusive. It will be assumed that code 5, connected to conductor 316, is the ringing code of the subscriber at station B. The 15 ringing circuit is as follows: code interrupter machine, conductor 316, wiper 311 of the code switch, conductor 258, armature 229, armature 234, armature 228, conductor 244, wiper 307 and its associated fourth bank contact, conductor 317 20 of the called subscriber's line, through the ringers of all subscribers' stations whose ringers are connected through conductor 317 to ground. The code ring transmitted over this circuit rings all the bells connected to conductor 317, but the 25 ringing code transmitted indicates to the subscriber at station B that he is wanted. It should be noted that a portion of the ringing current passes through condenser 260, through the repeating coil, over the called subscriber's line, and gives the calling subscriber an audible ringing tone as an indication that the bell at the called 30 station is being rung.

When the subscriber at station B answers the call, the grounded code ringing current which was 35 extended over the circuit just traced, is connected to conductor 318 of the called subscriber's line in response to the removal of the receiver at station B. This circuit is extended, due to the removal of the receiver by the subscriber at station B, over 40 conductor 318, bank contact and wiper 308 of the connector, conductor 243, armature 226, armature 233, armature 230, conductor 254, wiper 312, and the associated fifth bank contact of the code switch, conductor 255, lower winding of ring cut-off relay 206 to battery. Armature 260 of the 45 ring cut-off relay 206, is adjusted to make its X contact first, thereby completing a circuit from grounded conductor 91, armature 260, upper and lower windings of relay 206 to battery. The 50 grounded ringing code circuit over which ring cut-off relay 206 was initially operated over its lower winding has sufficient resistance in its circuit to prevent its shorting out of the upper winding of relay 206. Relay 206 locks up over the 55 circuit just described, and disconnects the ringing current from the called subscriber's line at the back contacts of armatures 233 and 234, and at their front contacts connects the called subscriber's line through the repeating coil and back-bridge relay 205. The opening of armatures 212 and 235 by relay 206 does not affect the circuit 60 operation at this time.

The back-bridge relay 205, which was connected to the called line when the ring-cut-off relay 65 operated, is energized over the following circuit: battery, upper winding of back-bridge relay 205, the normally closed contacts controlled by armature 242, armature 261, lower right-hand winding of the repeating coil, armature 234, and its front 70 contact, armature 228, conductor 244, wiper 307 and the associated fourth bank contacts of the connector, conductor 317 of the called subscriber's line, station B, conductor 318 of the called subscriber's line, wiper 308 and associated fourth 75 bank contact of the connector switch, conductor

234, armature 226, armature 233 and its front contact, armature 237, upper right-hand winding of the repeating coil, armature 238, normally closed contacts controlled by armature 241, lower winding of back-bridge relay 205 to ground. In 5 response to the operation of back-bridge relay 205, supervisory relay 18 is operated from ground at armature 262.

Supervisory relay 18 performs several operations. At armature 65 it disconnects the supervisory timer relay 15 which restores to normal, thereby disconnecting the link from the timer equipment. The ground normally supplied from the cut-off conductor CO of the timer equipment is now supplied from the normally closed contacts controlled by armature 61. At armature 101, supervisory relay 18 opens the start circuit to the code interrupter, and at armatures 113 and 114 causes the reversal of current in the calling subscriber's line. The operation of other armatures controlled by supervisory relay 18 is of no importance at the present time. The reversal of current on the calling subscriber's line may be used for either metering or for supervision when either of these services are required.

The required connection has now been completed. The calling line is supplied with talking current through the windings of line relay 19 and the left-hand windings of the repeating coil. The called line is supplied with talking current from the back-bridge relay 205 and the right-hand windings of the repeating coil. The talking circuit has been drawn in by means of heavy lines and will therefore be readily traced.

The release of local call connections, similar to the call described, is under control of the calling party. However, it will be assumed in this case that the called subscriber hangs up his receiver first. When the subscriber at station B replaces his receiver on the switchhook the circuit for the back-bridge relay 205 is opened. Back-bridge relay 205 accordingly falls back and opens the circuit for supervisory relay 18 which also restores to normal. At armatures 113 and 114, relay 18 again causes the reversal of battery to the calling line for supervision. It grounds the interrupter start lead at armature 101, and at armature 65 prepares the circuit for the supervisory timer relay 15. As has been explained before, the supervisory timer relay 15 operates at the beginning 40 of a time cycle from the timer when the time pulse lead TP is momentarily grounded. When 45 this occurs, time-pulse relay 15 operates and locks itself up at armature 64. The release of the connection is now under control of the timer which 50 will remove the ground from the cut-off conductor CO after a predetermined time interval has 55 elapsed.

For the purpose of describing the release of the connection under control of the timing equipment, it will be assumed that the calling subscriber has failed to hang up his receiver after the called subscriber has released the connection. It may be well to mention at this time that the timing equipment would also control the release of the link circuit if a calling subscriber should fail to dial after having removed his receiver to make a call; or if there is a permanent or a short on the line; or if a called subscriber fails to answer a call within a predetermined time interval. 60 When the timing equipment has operated through 65 a complete cycle, ground is removed from the cut-off conductor CO. Accordingly, cut-off relay 2 of the line circuit which was locked up over 70 a circuit including the grounded CO conductor 75

falls back. Relay 2, upon restoring, again connects the line relay 1 to the line. Line relay 1 operates over the previously traced circuit including the calling subscriber's equipment at station A, and at armature 24 completes a locking circuit for the lockout relay 3. Lock-out relay 3 is a slow-to-release relay and falls back slowly when its initial energizing circuit is opened by the release of cut-off relay 2. The line relay 1 also grounds the conductor 31 to make the line busy at the test contacts of the connector bank. The line circuit of the calling subscriber's line is now locked out from the link. Consequently, the subscribers on the same line with station A cannot make calls nor can they receive calls. The line circuit will remain locked out until such time as the subscriber at station A replaces his receiver or, if the line is shorted, the short is removed. When this occurs, the line relay 1 restores to normal, therefore by removing the ground from conductor 31 and also opening the locking circuit for lockout relay 3.

Referring again to the removal of ground from the cut-off conductor CO by the timer, it will be noted that the previously described holding circuit for the upper winding of the switching relay 9 is also opened. Switching relay 9 falls back, and at armatures 109 and 110 opens the energizing circuit of line relay 19, and at armature 120 opens points in the circuit from the pick-up conductor PU. In addition, at armatures 121 and 122 and their respective bank contacts, switching relay 9 also prepares a self-interrupting circuit for the rotary magnets of the connector and code switch of the link. Line relay 19, upon falling back, opens the circuit for the lock-pulse relay 12 which also falls back, thereby opening the circuit to release relay 16.

Referring now to the auxiliary release relay 17, it will be noted that the energizing circuit for relay 17 was opened at the time ground was removed from the cut-off conductor CO by the timer. When auxiliary release relay 17 fell back it opened the locking circuit for supervisory timer relay 15 at armature 55. At armatures 100 and 101, release relays 16 and 17 remove ground from conductor 91 thereby causing the release of ring-cut-off relay 206 and pick-up and switching relay 207. When pick-up and switching relay 207 restores to normal it completes the self-interrupting circuit for controlling the rotary magnet 301 of the connector and rotary magnet 302 of the code switch to advance their respective wipers to the normal or "home" position of the respective bank contacts.

Referring now to the bank contacts of the connector and also to the bank contacts of the code switch, it will be noted that wipers 304-308, inclusive, of the connector and wipers 309-312, inclusive, of the code switch are shown in engagement with the normal or "home" bank contacts of the switch. If the wipers of the connector switch were advanced twelve steps they would again engage another normal or "home" bank contact. The same is true of the code switch, however the code switch only need advance its wipers eleven steps to again engage a normal or "home" bank contact. It is well understood by those familiar with this type of switch, that the bank contacts of the first group may be multiplied with the bank contacts in a second group on the same switch. Therefore, the second appearance of the bank contacts of the connector switch has not been shown since it is a direct multiple of what is shown in the first appearance.

The multiplying of the bank contacts of the code switch between the first and second group is the same as, described in connection with the connector bank contacts.

Since the wipers 304-308, inclusive, of the connector are in engagement with the bank contact to which line 45 is connected, and since wipers 309-312, inclusive, of the code switch are in engagement with the set of bank contacts to which conductor 316 is connected, the following circuit 10 for restoring the wipers of the code switch to normal may be traced. Grounded wiper 304 of the connector switch, conductor 96 which is multiplied to the contacts engaged by wiper 304, armature 122, armature 123, conductor 97, armature 232, conductor 256, wiper 310 of the code switch, conductor 249 which is multiplied to the contacts engaged by wiper 310, armature 261, armature 319, winding of rotary magnet 302, to battery. The rotary magnet 302 energizes and 20 opens its armature 319, thereby opening the energizing circuit for rotary magnet 302. When the rotary magnet falls back the wipers of the switch are advanced one step. Since there is no alteration in the multiplying of the bank contacts 25 of which wiper 310 of the code switch has access, the rotary magnet 302 continues to operate and break its own circuit at armature 319 until wiper 310 engages the same contact to which conductor 251 is connected. The circuit of the rotary magnet 302 is now transferred from conductor 249 to conductor 251. The wipers 309-312, inclusive, of the code switch have now been advanced to their normal or "home" bank contacts, and are in a position to be controlled by a calling subscriber to 35 again select a desired code ring.

The previously traced circuit from the grounded wiper 304 of the connector, to wiper 310 of the code switch is now extended by way of conductor 251, armature 219, conductor 245, armature 320 40 of the rotary magnet 301, winding of rotary magnet 301, to battery. Rotary magnet 301 operates over this circuit and at armature 320 opens the energizing circuit for itself. Upon releasing, rotary magnet 301 advances its wipers 304-308, inclusive, to the next set of bank contacts. The set of wipers continue to advance over the bank contact of the connector, under control of the self-interrupting circuit of the rotary magnet 301, until the wiper 304 leaves the bank contacts which are multiplied to conductor 96 and 45 engages the bank contact connected to conductor 95. The transferring of the circuit from conductor 96 to conductor 95 does not affect the self-interrupting circuit for the rotary magnet 50 301, because the circuit is now maintained over the back contacts of armatures 121 and 122 of the switching relay 9. Therefore, the rotary magnet 302 continues to advance its wipers 304-308, inclusive, until wiper 304 engages the normal 55 or "home" bank contact. When wipers 308-308 engage the home bank contact the circuit for the rotary magnet 301 is accordingly opened. The link circuit is now at normal and may be used to 60 find another calling subscriber's line and to extend a connection.

In the description of the release of the link, it was assumed that the called subscriber hung up his receiver first and that the calling subscriber failed to hang up his receiver, and that 70 the release of the connection was under control of the timer equipment. If the calling subscriber had released the connection first, by restoring his receiver, the release of the link is substantially as has been described with the exception that the 75

line circuit of the calling subscriber's line is not locked out. When the calling subscriber hangs up his receiver the line relay 19 falls back and opens the circuit for lock-pulse relay 12. Lock-pulse relay 12 opens the circuit of release relay 16. Release relay 16 falls back and disconnects the grounded cut-off conductor CO of the timer at armature 54. When this ground is removed switching relay 9, auxiliary release relay 17, and cut-off relay 2 of the line switch, are all restored to normal. Line relay 1 of the line circuit is now bridged across the line, but does not energize because the loop circuit including the subscriber's line is now open. Lock-out relay 3 of the line circuit is also released. The remaining portion of the link circuit is released in the same manner as has been described previously.

A description will now be given to explain how a subscriber, such as a subscriber at station A, calls for another subscriber on his own line. That is what is commonly termed a reverting call.

When the receiver is removed at station A, the same operations take place as have been described, with the result that the calling line is picked up by the finder switch of the link. Assuming that the link shown on the drawings is used, the finder switch will establish a connection to the calling line, and circuits will be completed automatically for placing the connector portion of the link under control of the calling subscriber's dial. The calling subscriber now dials the first digit of the wanted subscriber's number, thereby controlling the connector portion of the finder switch to advance its wipers to select the wanted line. The subscriber now dials the last digit of the number, thereby controlling the code switch to advance its wipers. Following the operation of the code switch, the called line is tested in the manner hereinbefore described, and of course it is bound to be busy. This, it will be understood, is because the called line is also the calling line.

Upon receiving the busy signal, the calling subscriber hangs up his receiver. The subscribers on party lines have special instructions, and therefore, such a subscriber knows that when he calls a party on his own line he can expect to get the busy signal and that the proper procedure in such a case is to hang up his receiver and wait a sufficient length of time for the signalling operation to take place.

When the receiver is replaced at station A, relay 19 falls back, followed by the falling back of lock-pulse relay 12. Accordingly, the slow-acting release relay 16 deenergizes. Relay 16, upon deenergizing, removes the ground potential from the wiper 60 of the finder switch and the upper winding of switching relay 9 at armature 54, but prior to this a circuit has been connected up in a manner which will now be explained. When lock-pulse relay 12 falls back it closes a circuit, at armature 116 and its back contact, from the grounded cut-off conductor CO, armature 61, armature 57 and its front contact, armature 116 and its back contact, armature 221, armature 259, armature 263, conductor 248, to test wiper 306. The test wiper is now in engagement with a test contact to which the private normal conductor 31 of the calling line is connected, so that ground is extended by way of conductor 31, back contact of armature 23 of line relay 1, Fig. 1, armature 27 of the cut-off relay 2, conductor 32, to test wiper 60. Thus ground is maintained on conductor 32 and wiper 60 to hold

cut-off relay 2, switching relay 9, and auxiliary release relay 17 energized so as to maintain the connection after the calling party hangs up his receiver.

When the release relay 16 falls back, it completes a circuit at the back contacts of armature 54, which extends from the grounded test wiper 60 of the finder, by way of armature 108, armature 54 and its back contact, conductor 84, armature 264 of the busy relay 209, armature 10 235, conductor 85, winding of reverting call relay 11, to battery. Reverting call relay 11 operates, and due to its adjustment closes armature 125 and its X contact first to transfer the grounded conductor including wiper 60 from armature 108 of the switching relay 9. When the reverting call relay 11 is fully energized, the circuit for switching relay 9 is opened at armature 106; the initial energizing circuit for relay 11 is opened at the back contact of armature 20 63; and at the front contact of armature 63 a locking circuit is completed for relay 11. At armature 124, reverting call relay 11 connects the pick-up lead through to the pick-up and switching relay 207. When switching relay 9 falls back it removes the line relay 19 from the line wipers of the finder portion of the link circuit and prepares the self-interrupting circuits for the rotary magnets of the connector and code switch portion of the link.

When the code interrupter is in a position to transmit a ringing code a ground pulse is transmitted over the pick-up conductor causing the operation of pick-up and switching relay 207, which locks itself up over its lower winding by 35 way of armature 231 to the grounded conductor 91. The ringing code of the called subscriber is transmitted over the previously traced circuit which in this case includes the line normals of the line circuit as shown in Fig. 1 and line conductors 28 and 29. It should be mentioned at this point that during the signalling operation pick-up relay 207 at armature 227 disconnects the busy tone from the calling subscriber's line in order to prevent the ringing current from back-45 ing up on the busy leads, which may at this time be connected up in the other link circuit. This condition only occurs on reverting calls, since it is only on a call of this kind that the busy lead is connected up during the ringing 50 operation, this is due to the fact that in a reverting call the busy relay 209 is energized.

When the called subscriber answers his telephone, the removal of the receiver closes a circuit in the previously described manner for operating ring-cut-off relay 206. The ring-cut-off relay connects up the back-bridge relay 205 to the line which accordingly operates, and at armature 262 completes the operating circuit for supervisory relay 18. At armature 212, ring-cut-off relay 206 opens the circuit of auxiliary release relay 17. Relay 17, upon falling back, opens the previously traced circuit for grounding the private normal conductor 31 of the line circuit at armature 57. When ground is removed from the normal conductor 31 by the deenergization of auxiliary release relay 17, cut-off relay 2 of the line circuit falls back. The relays of the link circuit and the wipers of the connector and code switch portion of the link circuit are restored to 70 normal in the same manner as described in connection with making local calls.

Considering now the effect on the line circuit when ground is removed from the normal conductor 31 and cut-off relay 2 falls back. This 76

connects up line relay 1, which promptly energizes over the line, since the subscriber on the line who has been called by the subscriber at station A on the same line has his receiver off. 5 The falling back of cut-off relay 2 opens the circuit of lock-out relay 3, but this relay is slow-acting and it is locked up by the line relay 1 over a circuit which includes armatures 24 and 25. Relay 3 keeps the start conductor 30 clear of ground, which would otherwise be applied to it at armature 24 of the line relay, and it also maintains the winding of the cut-off relay 2 separated from the conductor 32, extending to the test contacts of the finder by way of armature 22 of the line relay. The line is marked busy in the banks of the connector by ground applied to the private normal conductor 31 at armature 23 of the line relay 1.

Talking battery is fed to the line through the 20 winding of line relay 1, and the line equipment is therefore the only apparatus that is in use during conversation on a call of this character. The link circuit which was used to set up the connection has been restored to normal as has been 25 previously described and may be used in another connection.

The subscriber at substation A in the call which has just been described, knows when the called subscriber on his line answers, because the ringer 30 at station A has stopped ringing. Since the bell at station A is connected to the same side of the line as the bell of the called subscriber, both bells will ring in parallel and when his own bell stops ringing the subscriber at station A knows that the 35 subscriber he has called has answered. If a station is called, at which the bell is connected to the other side of the line, the subscriber at substation A will not hear the ringing, but he will wait, according to instructions, a long enough 40 time to permit the wanted subscriber's bell to be rung several times, when he will remove his receiver.

The operations which take place in setting up a connection to a subscriber in a distant automatic exchange will now be described. Certain contacts in the bank of the connector portion of the link circuit, have been set aside for trunk lines extending to a distant automatic exchange. For the purpose of this description it will be assumed that the trunk line composed of conductors 45 T1 and T2 extending from the exchange herein described to a distant automatic exchange with which service is to be given. The trunk line conductors T1 and T2 may be connected to a regular subscriber's line equipment, similar to the subscriber's line equipment shown in Fig. 4. The automatic switches at the distant exchange may be similar to the switches and circuits of the 50 John E. Ostline application, Serial No. 724,238, filed May 7, 1934.

Since two trunk lines are provided for handling calls to the automatic exchange in question, the connector portion of the link shown in the drawings must be arranged to operate as a rotary automatic selecting connector. This merely means that the subscriber in calling the distant exchange will dial the number of the first trunk line in the group. If this trunk line is idle it 55 will be seized and the connection will be extended thereover. If the first trunk line is busy, however, the rotary magnet will automatically advance the wipers of the connector to the next trunk line. If the second trunk line is busy the 60 calling subscriber will receive the busy signal

indicating that the trunk lines to the distant exchange are in use.

It will be assumed now that the subscriber at station A, Fig. 1, desires to extend a connection to the distant automatic exchange, shown in part 5 on Fig. 4. In order to accomplish this, the subscriber must dial a preliminary number 01, followed by the regular number of the desired subscriber in the distant automatic exchange. When the receiver is removed at station A, the previously described operations take place, by means of which the calling line is picked up by an idle link circuit. It will be assumed that the link circuit shown in Figs. 1, 2, and 3 of the drawings is used. When the subscriber dials the first digit 10 0, ten impulses are transmitted to the rotary magnet 301 in the same manner as has been described in connection with local calls. The wipers 304-308, inclusive, of the connector, advance to the contacts of the connector banks to which 15 the first trunk line is connected, in other words, the tenth set of bank contacts. When wiper 304 engages its tenth bank contact, a circuit is completed from ground at wiper 304, conductor 95, armature 121 and its front contact, conductor 20 94, armature 233 and front contact of the operated units series relay 210, both windings of the ring cut-off relay 206 in series, to battery. Ring-cut-off relay 206 operates, thereby preventing the transmission of the ringing current over the 25 trunk line after the dialling of the second digit. Wiper 305, of the connector, prepares the circuit for automatic trunk selection when it engages the contact to which conductor 246 is connected.

If the trunk line to the distant automatic exchange is busy when the wipers of the connector switch engage the trunk line, test wiper 306 encounters a ground potential on conductor 321. A circuit is then completed for the busy test relay 209, from grounded conductor 321, wiper 306, 40 conductor 248, armature 260 and its front contact, winding of busy test relay 209, to battery. Relay 209 operates and at armature 266 prepares a self-interrupting circuit for the rotary magnet 301 of the connector switch. Tens series relay 208 falls 45 back after the first digit has been dialled and at armature 219 completes the self-interrupting circuit for the rotary magnet 301. The circuit for operating the rotary magnet is completed as follows: wiper 305 of the connector which is 50 grounded by way of conductor 91, its associated tenth bank contact, conductor 246, armature 266, armature 219, conductor 245, contacts 320 of the rotary magnet 301, winding of rotary magnet 301, to battery. Rotary magnet 301 operates and 55 opens its own energizing circuit at armature 320 and advances its wipers 304-308, inclusive, to the next set of bank contacts. Wiper 305 has now been disengaged from the self-interrupting circuit for the rotary magnet 301, thereby preventing 60 the rotary magnet from energizing again to advance its wipers, if the second trunk in the trunk group is busy.

If the second trunk in the group is also busy, ground potential will be encountered by the test 65 wiper 306 of the connector, thereby maintaining the busy relay 209 energized. Busy relay 209 prevents relay 202 from operating at armature 265, and at armature 259 prepares a busy circuit to the calling subscriber. After the dialling of the sec- 70 on digit, relays 210 and 211 fall back, as has been described hereinbefore, and completes the locking circuit for the busy relay 209. When auxiliary relay 211 falls back the busy tone is transmitted to the calling subscriber who will hang up his 75

receiver. The link circuit is restored to normal and is available for another connection. If the calling subscriber should fail to hang up his receiver the time equipment will complete its pre-determined time cycle and will cause the link circuit to be released in the same manner as described before.

It will be assumed now that the trunk line is found to be idle, and for convenience the first trunk of the group as indicated on the drawings is selected. Therefore, test wiper 306 of the connector does not encounter ground potential on conductor 321, and busy test relay 209 is not energized.

The calling subscriber may now dial the digit 1. The rotary magnet 302 of the code switch is operated as before, advancing its wipers 309-312, inclusive, one step. Since the ring-cut-off relay 202 has disconnected the circuit for transmitting ringing current to the trunk line, the advancement of the wipers by the code switch to select the ringing current is not important at the present time. After the dialling of the second digit, unit series relay 210 falls back and opens the circuit for auxiliary relay 211. At armature 223 and its back contact, unit series relay 210 upon falling back, completes a circuit for the change-over relay 202. This circuit may be traced as follows: battery, winding of relay 202, terminal M jumpered to terminal N, armature 265, armature 223, conductor 94, armature 121, conductor 95, tenth bank contact and wiper 304 of the connector, to ground. Since the call being described is to an automatic exchange, the change-over relay 201 which is used on toll calls to a manual exchange is disconnected and the change-over relay which is used on toll calls to automatic exchanges is connected. In addition, relay 210 prepares the circuit for pick-up and switching relay 207 at armature 225. The pick-up and switching relay 207 is operated when the pick-up conductor PU is grounded and locks itself up at armature 231 to the grounded conductor 91. At armatures 226 and 228, relay 207 connects the trunk line through to both windings of the repeating coil. When relay 202 operates, it opens the circuit for supervisory timer relay 15 at armature 214, thereby preventing the link circuit from being released under control of the timer equipment. When auxiliary relay 211 falls back ground is forwarded at armature 260 over conductor 248 and test wiper 306 to the private normal condition 321 to operate the cut-off relay in the line circuit of the trunk line and also to make the trunk busy at the connector bank terminals of the second link.

Referring again to the operation of change-over relay 202, it will be noted that at armature 239 ground is placed on conductor 99 in order to place the release of the link circuit under the control of both the calling and called parties, and at armatures 261 and 238 it disconnects the back-bridge relay 205 from the trunk line, and at the same time at armature 238 and its front contact completes a loop circuit over the trunk line, which will be described later. At armature 240, relay 202 completes a circuit from the grounded conductor 91, armature 240, lower winding of pick-up and switching relay 207, to battery. This circuit is completed to insure the operation of relay 207 to cut the trunk line through to the automatic exchange. It is quite possible that the pick-up conductor has not been grounded before relay 202 operates. Therefore, relay 207 is operated even if the pick-up conductor PU has not been grounded.

When change-over relay 202 operated it completed a loop circuit over the trunk for the line relay 405 of the line equipment in the distant automatic exchange. The circuit for line relay 405 is as follows: battery, upper winding of line relay 405, armature 415, conductor 411, normally closed contacts controlled by armature 406, trunk conductor T2, wiper 307 and its associated tenth bank contact of the connector portion of the link, conductor 244, armature 228, 10 armature 234 and its front contact, lower right-hand winding of the repeating coil, resistance 261, armature 238, upper right-hand winding of the repeating coil, conductor 75, armature 136, armature 135, conductor 13, armature 233 and 15 its front contact, armature 226, conductor 243, wiper 308 and its associated tenth bank contact of the connector portion of the link circuit, trunk line conductor T1, normally closed contacts controlled by armature 407, conductor 412, lower 20 winding of line relay 405, armature 416, to ground. The two relays, shown to the left of the dash line in Fig. 4, are provided in the trunk line to prevent the release of the C. A. X. link circuit until the called subscriber has released 25 the connection. Therefore, when line relay 405 operates, a circuit is completed from ground at armature 418, armature 413, winding of start relay 402, to battery. Start relay 402 operates and grounds the finder start conductor to the 30 allotter at armature 409, and at armature 410 prepares a circuit for the battery reversing relay 401. Line relay 405 prepares a circuit for cut-off relay 404 at armature 419, and at armature 420 completes an energizing circuit for battery reversing relay 401 and by the same operation grounds the SN conductor to busy the calling line in the banks of the connector switch. Relay 401 operates and at armature 408 completes a locking circuit for itself from the ground at 40 armature 420 of the line relay. The reversal of battery at armatures 406 and 407 by the operation of relay 401 has no effect at this time due to the fact that the circuit for the hold relay 203 of the C. A. X. link circuit is opened at armature 136 by release relay 16. Therefore, it will be understood that the hold relay 203 cannot operate until release relay 16 is deenergized. Due to the grounding of the finder start lead by the operation of relay 402 of the distant automatic exchange, a finder in the link eventually selects the calling line. When this takes place, ground on conductor S, which is connected to the finder bank, is extended by way of armature 419, armature 414, and winding of cut-off relay 404, 55 to battery. Cut-off relay 404 operates over this circuit and locks itself to the grounded S conductor. At armatures 415 and 416, cut-off relay 404 opens the circuit for line relay 405, and at the front contact of armature 416 completes an 60 energizing circuit for lock-out relay 403. Lock-out relay 403 operates and opens the circuit to start relay 402 at armature 413, which accordingly falls back. When line relay 405 de-energizes, it opens the initial energizing circuit 65 for the reverse battery relay 401 which is slow to release, due to the shunt around its winding. Relay 401 is operated again before armature 408 is opened, over the following circuit: grounded conductor S of the finder bank, armature 417, 70 armature 420, armature 408, winding of battery reversing relay 401, to battery. Trunk conductors 411 and 412 are extended through the wipers of the finder switch to the line relay in the link circuit at the distant exchange. The line 75

relay in the link circuit is operated over the loop in the same manner that the line relay 405 of the line equipment was operated. The automatic switches in the distant exchange are now 5 in a position to receive the impulses transmitted by the operation of the calling device at station A.

The link circuit is now in a position to receive impulses transmitted by the subscriber at station A and to retransmit them to set the switches 10 in the distant automatic exchange to the desired subscriber's line. The subscriber at station A now dials the number of the wanted subscriber at the distant automatic exchange. Line relay 19 follows the interruptions of its circuit by the dial 15 springs of the calling subscriber's station. The first time this circuit is opened the lock-pulse relay 12 falls back. The operation of the line relay 19 and the lock-pulse relay 12 during the 20 dialling period has been described in detail hereinbefore. When lock-pulse relay 12 falls back a circuit is now completed for the #1 pulse timer relay 14 from ground at either armature 100 or armature 111, armature 126, conductor 90, armature 25 262, conductor 89, armature 140, lower winding of #1 pulse timer relay 14, to battery. Relay 14 operates and completes a locking circuit for the slow-to-release relay 16 at armature 133, it completes the circuit for the lower winding of 30 #2 pulse timer relay 13 at armature 130, and at armature 135 opens the circuit for the line relay of the link in the distant automatic exchange. The short circuit around the upper winding of 35 relay 14, completed at armature 134, makes the relay slow to release. The circuit for #2 pulse timer relay 13 is completed from ground at armature 111, armature 130, armature 127, lower winding of relay 13 to battery. Relay 13 has a short circuit around its upper winding and is consequently somewhat slow to operate. Upon operating 40 relay 13 completes a locking circuit for itself at armature 129, from ground at armature 111, and at armature 140 opens the initial energizing circuit for the lower winding of relay 14, and at armature 128 prepares the operating circuit 45 for the lock-pulse relay 12. Relay 14 falls back, and at armature 135 again closes the loop circuit over the trunk line to the line relay in the link circuit at the distant exchange. When the 50 impulse springs at the calling subscriber's dial are closed again, line relay 19 operates and completes the circuit for operating lock-pulse relay 12. Relay 12 operates and completes a locking circuit for itself and at armature 127 opens the 55 circuit for #2 pulse timer relay 13. At armature 126, relay 12 opens a point in the energizing circuit for relay 14.

Line relay 19, lock-pulse relay 12, and the pulse timer relays 13 and 14 go through the above described cycle of operations during each interruption of the dial or impulse springs at the subscriber's station. Relay 14, through its armature 135, repeats the impulses to the distant automatic exchange. The operating and release characteristic of relays 14 and 13 are such that the repeated pulse action through the armature 135 is approximately the same as the pulse sent out by a standard dial.

The impulses transmitted over the trunk line 70 follow the number dialled by the calling subscriber and the automatic switches at the distant exchange are connected to the wanted subscriber's line in the well known manner. The wanted subscriber is signalled by the ringing

equipment in the distant automatic exchange, and answers his telephone.

When the conversation between the calling and called subscriber has been completed they will hang up their receivers. It will be assumed that the subscriber at station A replaces his receiver first, thereby opening the circuit for line relay 19 of the link circuit. Line relay 19 opens the circuit for lock-pulse relay 12, which also falls back. When lock-pulse relay 12 falls back, the 10 previously described operating cycle of the pulse timer relays 13 and 14 will be again closed, and the momentary opening of contacts 135 will transmit another impulse over the trunk line to the 15 distant automatic exchange. However, this is of no consequence at this time since the impulse transmitted will not affect the switches at the distant exchange. Pulse timer relay 13 remains energized over a circuit including armature 129 and opens the circuit for relay 14. Release relay 20 16 now falls back and completes a circuit for the hold relay 203 at armature 136 and at the front contact of armature 136 the loop circuit, over which the line relay in the distant automatic exchange is maintained operated, is opened. The 25 line relay referred to is not the line relay 405 shown in Fig. 4, but is the line relay of the link circuit that receives the impulses transmitted over the trunk line. The circuit for energizing hold relay 203 is as follows: from ground, winding of relay 203, armature 236, conductor 74, armature 136, armature 135, conductor 73, armature 233, armature 226, conductor 243, wiper 308 and its associated tenth bank contact, trunk line conductor T1, armature 407 and its front contact, conductor 411, over the negative (—) conductor by way of the finder switch wiper, to the winding of the line relay, to battery. The winding of the hold relay 203 is of a high resistance, and the winding of the line relay in the link 40 circuit at the distant exchange is of considerably lower resistance. Therefore, the hold relay 203 operates but the line relay does not operate. Upon operating, relay 203 completes a circuit from ground at its upper armature, armature 45 213, and conductor 71 to maintain auxiliary release relay 17 in an energized position. As long as auxiliary release relay 17 remains operated the link circuit at the C. A. X. will not release. Since the called subscriber at the distant automatic 50 exchange has hung up the receiver to release the connection, the equipment at the distant exchange restores to normal. When the switches at the distant exchange have been released, ground is removed from the S conductor, thereby 55 opening the locking circuit for cut-off relay 404, and battery reversing relay 401 in parallel. In addition, ground is removed from the SN conductor extending to the connector banks, thereby removing the busy condition from the test contacts in the banks of the connector. Relays 404 and 401 fall back when ground is removed from the S conductor, and at armatures 406 and 407 the reversal maintained over the trunk conductors T1 and T2 is restored to normal. Therefore, 60 the battery potential applied to conductor 411 and trunk conductor T1 to maintain the hold relay 203 in the C. A. X. operated, is now disconnected from trunk conductor T1 and connected to trunk conductor T2. The circuit to the hold 65 relay 203 is no longer maintained, and it accordingly restores to normal. The deenergization of cut-off relay 404 of the line equipment in the distant automatic exchange permits lockout relay 403 to fall back, and at armatures 416 and 415 70 75

again connects the line relay 405 to line conductors 411 and 412. When the hold relay 203 in the C. A. X. falls back, it opens the circuit for the auxiliary release relay 17, which upon deenergizing permits the link circuit in the C. A. X. to restore to normal in the same manner as described before.

From the description of the above connection it will be understood that when a subscriber in the C. A. X. extends a connection over the trunk line to a distant automatic exchange, that the release of the equipment in the C. A. X. is under the control of the called party. This particular arrangement is provided to prevent another subscriber in the C. A. X. from seizing a trunk to a distant automatic exchange when the equipment thereat has not completely restored to normal. By holding the C. A. X. equipment in an operated condition, under control of the equipment at the distant automatic exchange, a subscriber in the C. A. X. is unable to select the trunk in use because of the busy condition maintained on the test contacts in the banks of the connector.

A call which is extended from a calling subscriber in the C. A. X. to a subscriber in a manual exchange will now be considered. It will be assumed for this purpose that the calling subscriber is the subscriber at station A. It will also be assumed that the trunk line conductors T1 and T2 shown between Figs. 3 and 4 of the drawings, terminate at a distant manual exchange in equipment similar to trunk TR shown on Fig. 7 in the John E. Ostline application, Ser. No. 724,238, filed May 7, 1934.

When the receiver is removed by the subscriber at station A, a link circuit is taken for use in the manner previously described. It will be assumed that the link circuits shown on the drawings is the one which is connected to the calling subscriber's line after the removal of his receiver. It should be clearly understood that two trunk lines, which may be connected to the banks of the connector portion of the link circuit, will either terminate in a distant automatic exchange or a distant manual exchange.

The calling subscriber dials the number 01 and thereby controls the link circuit to select the trunk line to the distant manual exchange. A detailed description of the operation of the link circuit in selecting an idle trunk line has been described hereinbefore, in connection with establishing a connection between a local subscriber in the C. A. X. and a subscriber in a distant automatic exchange. Therefore, it will be assumed that the trunk line to the manual exchange in this case is idle, busy relay 209 has made the test and has fallen back, and after the dialling of the second digit the unit series relay 210 and auxiliary relay 211 have fallen back. When this occurs, a circuit is completed for the change-over relay 201, which is now connected up by a jumper from terminal N to terminal O and the jumper from terminal N to terminal N is removed, because the call being described is to a manual exchange. The circuit for operating change-over relay 201 is over the following path: battery, winding of relay 201, terminal O connected to terminal N, armature 265, armature 223, conductor 94, armature 121, conductor 95, wiper 304 and its associated tenth bank contact, to ground.

It will be remembered that the ring-cut-off relay 206 has been operated and is locked with both its windings in series to the grounded conductor 91, thereby disconnecting the ringing cur-

rent from the trunk line, and pick-up and switching relay 207 has been connected by way of its upper winding, armature 225, armature 259, conductor 93, armature 120, armature 49, to the pick-up conductor. When the pick-up conductor PU is grounded the pick-up and switching relay 207 operates and locks itself, by way of armature 231, to grounded conductor 91. At armatures 226 and 228, relay 207 connects the trunk line through to both windings of the repeating coil and the windings of the back-bridge relay.

By referring again to the operation of the change over relay 201, it will be noted that a circuit is completed for the reversing relay 204. This circuit may be traced from battery, winding of relay 204, armature 268, conductor 80, armature 116, armature 57 and its front contact, to the grounded cut-off conductor CO of the timer equipment. In addition, a circuit is completed at armature 271 for transmitting a ringing tone to the calling subscriber. The ringing current is transmitted from the code machine by way of contacts on the code switch, conductor 257, tone condenser, armature 271, conductor 98, armature 139, over the calling subscriber's line. The ringing tone, received by the calling subscriber, is an indication that the operator is being signalled. Relay 204, at armatures 241 and 242, reverses the battery in the trunk lines T1 and T2 causing the operation of a polarized relay in the manual exchange. The polarized relay, upon operating, completes a circuit to signal the operator at the manual exchange. Change-over relay 201 also prepares a locking circuit for release relay 16 at armature 259 and at armature 270 completes a circuit from the grounded conductor 91 to the lower winding of pick-up and switching relay 207. The latter circuit is completed to insure the operation of the pick-up and switching relay 207 to cut the trunk line through to the manual exchange. It is quite possible that the pick-up and switching relay 207 may not have operated from a ground pulse over the pick-up lead, if the connection should be established during the time interval between ground pulses over the pick-up conductor. The back-bridge relay 205, which furnishes talking battery over the trunk line to the manual exchange, is not operated over the loop circuit including both conductors of the trunk, because of a high resistance of one of the windings of the polarized relay at the manual exchange.

The operator at the distant exchange plugs in on the calling line when the signal is noted, and completes a circuit for shunting out the high resistance winding of the polarized relay. Sufficient current will now flow over the trunk conductors to permit the back-bridge relay 205 to operate. Back-bridge relay 205, upon operating, closes an obvious circuit for supervisory relay 18. Relay 18 operates and opens the circuit of supervisory timer relay 15 at armature 65, thereby disconnecting the timing equipment from the link circuit, and at armature 137 completes a locking circuit for release relay 16. In addition, relay 18 reverses battery over the calling subscriber's line for metering or supervision when that type of service is required, and at armature 139 disconnects the ringing tone from the calling subscriber's line, thereby indicating to the subscriber that the operator at the distant manual exchange has answered. The calling subscriber now gives the operator the number of the subscriber at the distant office.

If the subscriber at substation A desires to recall the operator for some reason or other, for example, to correct the number he has given the operator, he depresses his switchhook momentarily a number of times. When the receiver hook is depressed, the calling line circuit is broken and line relay 19 falls back, followed by the lock-pulse relay 12. Relay 12, upon deenergizing, breaks the circuit of battery reversing relay 204 at armature 116. The current flow over the trunk line to the polarized relay is again reversed, causing the polarized relay to restore to normal, and again signal the operator. When the switchhook at the calling subscriber's station is released, the line relay 19 and lock-pulse relay 12 are again energized, and at armature 116 the circuit is again completed for the reversing relay 204. When the reversing relay 204 operates again the current flow over the trunk line is again reversed so that the polarized relay at the distant exchange is again operated. During the momentary operation of line relays 19 and 12 the release relay is held operated from the change-over relay 201, thereby preventing the release of the link circuit. These operations may be repeated several times as the subscriber momentarily depresses his switchhook, resulting in the interrupted operation of the signal at the manual operator's position.

In view of the arrangement for recalling the operator which has just been described, it will be understood that the release of the connection is under the control of the operator. When the calling subscriber has completed his conversation with the wanted subscriber in the manual exchange and replaces his receiver, the described operations result in the operation of the signal at the operator's position. The operator will supervise the call and will ascertain whether the parties are through with the connection. She will then remove the plug from the jack. When the plug is removed from the jack, the short circuit around the high resistance winding of the polarized relay is removed, thereby causing the release of the back-bridge relay 205 in the link circuit of the C. A. X. Upon deenergizing, back-bridge relay 205 opens the circuit for supervisory relay 18 which also deenergizes. Relay 18 opens the circuit for release relay 16, at armature 137 and the remaining portion of the link circuit restores to normal in the same manner as has been described hereinbefore.

The invention having been described, what is considered to be new will be pointed out in the appended claims.

What is claimed is:

1. In a telephone system, a plurality of subscribers' lines, a plurality of finder-switches, an allotter common to all of said lines and said switches, means responsive to the initiation of a call by a subscriber on one of said lines for controlling said allotter to start all of said switches searching for the calling line, and means in said allotter for selecting one of said switches for connecting with said line and for preventing another switch from finding the calling line.

2. A starting arrangement for controlling the starting of a plurality of devices comprising, a start relay and a plurality of selecting relays, means for energizing and deenergizing said start relay, a first circuit for energizing one of said selecting relays in response to the first energization of said start relay, a second circuit for energizing a second selecting relay responsive to the first deenergization of said start relay, and a third

circuit for deenergizing the first selecting relay responsive to the second energization of said start relay.

3. A combination as set forth in claim 2, characterized by the provision of means controlled by the start relay in response to its second deenergization for deenergizing the second selecting relay.

4. In a relay allotter, a start relay, means for energizing and deenergizing said start relay, two differentially wound selecting relays, means controlled by the operation of said start relay for operating one of said selecting relays and for preventing the operation of the second of said selecting relays, means controlled by the operation of said first selecting relay for operating said second selecting relay responsive to the restoration of said start relay, and means controlled by said second selecting relay for restoring said first selecting relay to normal responsive to the reoperation of said start relay.

5. In a switching system, a pair of switching devices, an allotter common to said devices, a starting mechanism in said allotter, means responsive to the operation of said starting mechanism for starting said devices for continuous operation, means in said allotter controlled by and responsive to the operation of said starting mechanism for permitting one of said devices to cease operating and for causing the other device to continue to operate after said one device has ceased its operation.

6. In a telephone system, subscribers' lines, two finders for finding any one of said lines, an allotter common to said finders and said lines, means in said allotter responsive to the initiation of a call over one of said lines for simultaneously starting both of said finders, means in said allotter for determining the finder that shall find the calling line, and means responsive to the finding of said line by said determined finder for stopping both finders.

7. In a telephone system, subscribers' lines, two finders for finding any one of said lines, an allotter common to said finders and said lines, means in said allotter for starting both of said finders, said means responsive to the initiation of a call over one of said lines, means in said allotter for determining the finder that shall find the calling line, means responsive to the finding of said line by said determined finder for stopping both finders, and means responsive to the initiation of another call over one of said lines for restarting the idle finder to find said other line.

8. In a telephone system, a pair of finder switches, subscribers' lines, an allotter common to said switches and said lines, means responsive to the initiation of a call over one of said lines for simultaneously starting said finders in their line finding operation, means in said allotter for connecting only one of said switches to find said calling line, and means in said allotter and said connected finder switch for connecting the remaining finder switch to find successive calling lines as long as one switch is in use.

9. In a telephone system, a pair of switches, subscribers' lines, an allotter for alternately selecting said switches to find a calling subscriber's line, means for operating the selected switches to seize calling lines, and means controlled by a switch which has seized a calling line for connecting an unselected switch to find a calling line irrespective of the selection of said allotter.

10. In a telephone system, a trunk line, a first

- switch, a second switch, means for operating said first switch to connect with said trunk line and for connecting said second switch to the other end of said trunk line for establishing a telephone connection from a calling subscriber to a called subscriber over said switches and said trunk line, means controlled by said second switch for reversing the current over said trunk line responsive to said connection with said trunk line, a hold relay connected to one conductor of said trunk line when said calling subscriber replaces his receiver, said hold relay responsive to the reversed current supplied over one conductor of said trunk for preventing the release 10 of said first switch until said current reversing means is restored to normal.
11. In a telephone system, a trunk line to a distant automatic exchange, a switch for establishing connections over said trunk line, a calling subscriber's line connected to said switch, means in said switch controlled over one conductor of said trunk line operated responsive to the release of said line by a calling subscriber for preventing the disconnection of said switch 15 from said trunk line, and means at said distant exchange for releasing said switch.
12. In a telephone system, a trunk line to a distant automatic exchange, a switch for seizing said trunk line and extending a call thereover, a calling subscriber's line connected to said switch, means controlled over one conductor of said trunk line for preventing the release of said switch when said calling subscriber's line is disconnected, and current reversing means at 20 the distant automatic exchange for controlling the release of said switch.
13. In an automatic switch, a line relay, a stepping magnet, a pulse relay controlled at a front contact of said line relay, a circuit for 25 said stepping magnet controlled at the back contact of said pulse relay, a circuit including contacts on said magnet for priming said line relay, and contacts on said line relay for disconnecting said priming circuit.
14. In a telephone system, a trunk line, a switch for extending connections over said trunk line, a loop circuit from said switch including said trunk line for controlling automatic switches at the distant end of said trunk line, a pulse timer in said switch for interrupting the circuit over said loop, a line relay in said switch controlled by impulses, and an auxiliary relay controlled by said line relay for controlling said pulse timer to repeat said impulses over said loop circuit.
15. In a telephone system, a pair of finder switches, a plurality of subscribers' lines, an allotter, a test circuit for each of said switches, a starting circuit for said allotter responsive to the initiation of a call over one of said lines, means responsive to the operation of said starting circuit for starting both of said switches operating and for selecting one of said test circuits, means controlled over said selected test circuit for stopping the operation of both of said switches and for connecting the switch connected to the selected test circuit to said calling line, and means in said allotter responsive to successive operations of said starting circuit for alternately selecting said test circuits to alternately connect said switches to the calling line.
16. In a telephone system, a subscriber's line, a pair of switches for finding said line, an allotter, a test circuit for each of said switches, means responsive to a call over said line for controlling said allotter to start both of said switches and for controlling said test circuits so that only one of said switches can select said calling line, and means responsive to successive calls over said line for alternately controlling said test circuits so that said switches are alternately controlled to select said line. 5
17. In a telephone system, a trunk line to a distant automatic exchange, a switch for seizing said trunk line and extending a call thereover, a calling subscriber's line connected to said switch, means controlled over one conductor of said trunk line and operated when said calling subscriber's line is disconnected for preventing the release of said switch, and means at the distant automatic exchange for controlling the 15 release of said switch.
18. In a telephone system, a plurality of subscribers' lines, a plurality of switches for finding one of said lines, a start relay in each of said finder switches, a connector switch associated with each of said finder switches, means in one of said connector switches for preventing the operation of the start relay in the finder switch associated with said one connector switch, and means in said finder switch for connecting another of said finder switches for operation responsive to the initiation of a call over one of said subscribers' lines when said start relay is prevented from operating. 25
19. In a telephone system, a plurality of subscribers' lines, a pair of finder switches for finding one of said lines, an allotter for selecting one of said finder switches, a connector switch having a normal position associated with each of said finder switches, and means in one of 30 said connector switches effective in an off-normal position of said one connector switch for preventing the selection of the finder switch associated with said one connector switch irrespective of the selection of said allotter. 35
20. In a telephone system, a plurality of subscribers' lines, a pair of finder switches for finding one of said lines, an allotter for alternately selecting said finder switches to find a calling subscriber's line, a connector switch having a 40 normal position associated with each of said finder switches, means in one of said connector switches effective in an off-normal position of said one connector switch for preventing the selection of the finder switch associated with said one connector switch irrespective of the selection of said allotter. 45
21. In a telephone system, a plurality of subscribers' lines, a first finder-connector link, a second finder-connector link, an allotter for selecting one of said links, means in the connector portion of one of said links effective during the existence of an unstandard condition of the connector of said one link for preventing the selection of said one link, and means in said link and said allotter for selecting the other said link for operation responsive to the initiation of a call over one of said subscriber's lines irrespective of the selection by said allotter. 50

JOHN H. VOSS.
